METHOD FOR OBTAINING VARIOUS GASES AND RECOVERING BY-PRODUCTS

Application filed January 30, 1926, Serial No. 85,050, and in Belgium February 12, 1925.

This invention relates to a continuous process of low temperature distillation for solid fuels, the residue of which is preferably gasified by the method of fusion of the ashes employing the whole or part of the means described in my co-pending applications Serial No. 8,810, filed February 12, 1925, and Serial No. 32,790, filed May 25, 1925.

10 The process is applicable to the low temperature distillation of a moving mass of bituminous fuel, such as coal, lignite, oil shale and the like, subjected to the action of a counter-current of hot rising gases, such as those produced in a slagging gas producer, within an extended zone of distillation, the temperature gradient of which is very small. This zone of distillation is provided with contiguous series of internal 20 openings or orifices of suitable dimensions, so that the fuel contained within said zone virtually comprises a series of adjacent, narrow layers, each layer, which is a fraction of the fuel mass within the distillation zone, 25 corresponding to one series of orifices of the same isothermic region. These orifices are placed around the peripheries of the respective layers, and since no devices are inserted within the body of the fuel mass 30 itself for withdrawing vapor laden gases therefrom, the mass stands as a body void of empty spaces, except for those which are naturally due to the ordinary filling of a column with solid fuel of the type described.

35 Other series of external openings or orifices are provided with devices for the regulation and discharge of the fractional flows of gases and vapors evolved in each layer. The space between said internal and external 40 orifices comprises a series of collecting chambers which, being filled with vapor laden gases, thus provide a mass of gases surrounding the moving fuel body which acts as an effective insulating agent.

45 Owing to the reduced temperature gradient, the difference of temperatures between any two adjoining layers amounts to only a few degrees. Being gradually heated by the hot gases rising successively through 50 each layer, the fuel, provided that it is con-

veniently sized and that the fuel layers are not too extended, releases at each layer a single primary hydrocarbon portion with a definite boiling point; that is to say, a fractional distillate. 55

If the zone of distillation and the orifices of evacuation are given suitable shapes, dimensions and arrangements, condensation of the hydrocarbon vapors in the mass of fuel will be practically avoided, and the said 60 vapors will be carried away by gas flows and collected fractionally in the primary form, and separately, in condensers of any suitable type connected to each external evacuating orifice, or to each series of said orifices, according to the arrangement used. Alteration of the quality and reduction in the yield of the products, more particularly of those 65 of low boiling point, are thus prevented.

Owing to the shape of the fuel body subjected to distillation, and to the positions of the orifices around the peripheries of the layers, the gases and vapors of hydrocarbon portions are diverted from every portion of each layer and the isothermic surfaces 70 of said layers are practically parallel, although not necessarily horizontal. Owing to the balanced regimen of temperatures existing within the successive layers, there is no superheated portion of said layers 75 where the fractional primary hydrocarbon portions might be destroyed.

Wide and numerous orifices will ensure the evacuation of the gases and vapors at a relatively low speed, so that the carrying 80 away of dust is greatly reduced. By suitably regulating the gaseous flows escaping from the various orifices of the distillation zone, the temperature of each fuel layer of the distillation zone may be varied; this 85 renders it possible to also vary the grades of the condensable hydrocarbon portions carried away by the gases and to separate one from the other according to their specific gravities, that is, fractionating by 90 layers the fuel mass distillates, or to collect several of these fractional distillates together. With such a regulation, it is possible even to obtain separately all successive 95 grades of primary liquid hydrocarbon 100

portions, the specific gravities of which may be as low as 0.79 and the boiling point of which may be under 350° C. (and also above), according to the nature of the fuel distilled.

5 The regulation of the temperatures in the zone of distillation, and consequently the variation in quality and quantity of fractionate condensable by-products, may be obtained by utilizing the means enumerated in the above mentioned applications Serial No. 8,810 and Serial No. 32,790. As disclosed therein, an extended zone wherein distillation is effected at relatively low temperatures is maintained above a very hot, and preferably thin, zone of fusion in a slagging gas producer by creating in the fuel column, at selected levels, certain exothermic and endothermic effects whereby a 10 suitable regimen or gradient of temperatures is maintained extending from the hot zone of fusion to the top of the extended zone of distillation. The gas temperature within the lower portion of the fuel columns 15 may be around 1500° C. and above, and decreases progressively as the gases rise through the solids so as to be reduced to 350° C., and even less, at the upper level 20 of the charge.

25 30 The exothermal effects are produced by blowing at the bottom of the fuel column a blast of air or other fluid mixtures which contain free oxygen, or of other fluids producing with the fuel endothermic reactions, 35 said blast being heated to a temperature which is mainly dependent upon its free oxygen content and on the nature of the combustible mixture to be treated. The developed heat should be high enough to melt 40 completely the ashes and any additions in the fuel charge so that the molten residue is homogeneous and fluid.

45 For stable operation and maintenance of an extended zone of low temperature distillation having a slow gradient, it is sometimes necessary to localize at different levels in the fuel column certain endothermic effects of desired intensity. These endothermic effects may be produced by any of the 50 following steps:

55 a. The withdrawal or diversion of a portion of the hot gases of gasification at suitable levels of the fuel column, as between the zone of fusion and the zone of distillation;

60 b. The injection into the hot zone of the producer of fuel dust or fluids having endothermic reactions, such as steam, carbon dioxide, etc.;

65 c. The addition to the fuel of selected materials such as lean ore, limestone, iron and steel scraps, etc., the heating, fusion, volatilization, and decomposition of which at certain temperatures (and consequently

within certain layers of the fuel body) absorb heat.

All of these means may be used simultaneously, or any of them independently of the others, for the regulation and maintenance of a thin zone of fusion at high temperature and an extended zone of distillation at progressively decreasing low temperatures, from which gases are withdrawn carrying out a maximum quantity of high grade condensable hydrocarbon portions. Moreover, regulating the diversion of gases out of the zone of distillation also causes changes in the temperatures of solid materials reaching the zone of fusion, and thereby modifies the working conditions of said zone.

In order to make the invention clearly understood I will give, by way of example which in no way affects its scope, the following description of one application which will show how the fractionated zone of distillation is constituted, and how the gases and vapors of hydrocarbon portions carried away are extracted.

The fuel continuously charged at the top of a distillation retort of any suitable shape and section preferably forms a vertical column at the base of which the solid residue is gasified by the method of fusion of the ashes. The distillation zone of said column is provided with a series of annular boxes or chambers of generally frusto-conical shape arranged one above the other, one of their sides forming the walls of the shaft; their arrangement shows preferably no constriction of the profile line, each chamber being open in one or more ways to the gases and vapors evolved in the fuel body, and each being provided with one or more outlet pipes connected to a condensing plant (not shown).

Figures 1 to 4 inclusive, are diagrammatic vertical sectional views of a gas producer illustrating the flow of gases that may be secured through the same; and

Figure 5 is an enlarged side elevation and section of a portion of a producer illustrating the means for carrying out the present invention.

In the drawings there is shown, as one embodiment of the present invention, a slagging gas producer whose cylindrical or slightly conical shaft is provided at the top with a fuel charging apparatus F of a known, and preferably of a continuous distribution, type. The bottom portion or crucible of the producer is provided with at least one tap hole S for running off the slag and hole R for tapping molten metal. Above the crucible is a primary row of blast twyars B through which is blown a blast of air or other fluid mixture containing free oxygen. A second row of twyars E, situated above the blast twyars, serves to

inject into the hot zone of the producer fuel dust, or fluids with endothermic reactions such as steam or carbon dioxide. The producer shaft is also provided adjacent its top with gas outlets such as O, and with a suitable number of outlets O₁ arranged at a point situated above the level where the ashes are melted and below the bottom level of the distillation zone; T and T₁ are gas mains fitted with controlling apparatus such as valves V and V₁, and suitable suction fans (not shown). By varying the suction of said fans and the positions of valves V and V₁, a continuous flow of the gases within the producer can be maintained and regulated in any desired manner as indicated by arrows f₁, f₂ and f₃ in Figs. 1-4.

The gradual heating of the fuel mass filling the zone of distillation is effected progressively and as desired by allowing the passage therethrough of a sufficient proportion of the hot ascending combustible gases to give the desired temperatures at various portions of the column, which temperatures, it will be understood, can be continuously ascertained by the usual pyrometers. This passage or flow of hot ascending combustible gases is in turn effected by controlling valves V and V₁, as well as by regulating the blast supplied through twyvers B.

The extension of the zone of distillation is obtained by increasing the number of the outlet orifices O and their distance apart. It is then possible to maintain suitable graduated temperatures in the successive layers of the distillation zone, and to collect separately at each conveniently selected level the gases carrying the grade of primary condensable hydrocarbon portions evolved at said level. The hydrocarbon portions thus obtained from the various layers will vary from those having a maximum amount of low boiling oils to those having increasing percentages of high boiling oils containing tars and waxy products, according to the position of the layer in the distillation zone, and its corresponding level in the scale of temperatures, the grade of the products also depending upon the nature of the fuel submitted to distillation. It is also possible to collect separately a greater or lesser percentage of certain grades of primary condensable hydrocarbon portions by adjusting correspondingly the diverted portions of gases escaping at levels where the prevailing temperatures allow the removal of said grades of products. In the above cases, primary condensable hydrocarbon portions are obtained, which means that they remain unaltered in the producer and as evolved. They can be collected, however, not only separately at the various levels, but also as mixtures of those evolved at a plurality of levels with evidently some variation in quantities,

their production corresponding to the effects of the direct flow of ascending gases.

Again, if for a given fuel, which can yield the usual series of various hydrocarbon portions, the production of certain grades is desired regardless of the production of other grades, then the invention permits the easy obtainment of any particular grade of these hydrocarbon portions by maintaining a suitable balance of temperature and pressures at the level or levels where the required grade is evolved. Thus a high boiling oil can be obtained in maximum amounts by closing the valves at the top of the column and thereby causing the lighter products to pass through the lower hot zone, in which case, the production of primary condensable hydrocarbon portions of low boiling point will be less. Obviously, this results from the simultaneous effects of the flow of ascending gases and the counter-flow of a portion of them. In the same way, with a suitable regulation, it will be possible to obtain somewhat less of the portions with high boiling points and a correspondingly increased quantity of light condensable portions.

All such products above mentioned may be recovered separately (or may be mixed together and then recovered) in a condensing plant (not shown), if desired.

In order to carry out this fractional distillation process, the device illustrated in Figure 5 may be employed, the shape and details of which may vary within wide limits. This device constitutes the upper portion of a gas producer surrounding the zone of distillation, or the portion to be added to any existing gas producer which will also be preferably fitted with gas off-takes located above the scorchification zone and with an extended distillation zone. It comprises rings A, A₁, A₂, etc., mounted upon circular members M, said rings being preferably frusto-conical and forming with such members a series of annular collecting chambers C, C₁, C₂, etc., closed at their upper parts, each one being independent of the other and being connected with a by-product condensing plant (not shown) through separate pipes t, t₁, t₂, etc., provided with valves v, v¹, v², etc.

The frusto-conical shape preferably given to each successive ring of enlarged size allows the progressively retarded free descent of the fuel body, and takes care of the variable expansion or "swelling" peculiar to certain kinds of bituminous fuels. If apertures are provided in the rings, then the edges thereof may rest, if desired, upon members M, so that gas and vapors are diverted in each chamber through the open side of it or and through the apertures.

It is obvious that boxes C, C₁, C₂, etc., arranged at proper levels may be of different

sizes and numbers, and also can be insulated or not.

At will be seen from the arrows, the gases carrying with them the condensable by-products of distillation, pass separately through the wide, internal, annular openings or orifices in the boxes C, C₁, C₂, etc., and from there to the condensing plant (not shown), through the separate, external orifices or pipes t, t₁, t₂, etc., where the various grades of by-products so separated are then recovered.

Should it be desired, instead of collecting separately each primary grade of condensable hydrocarbon portions, to collect a mixture or mixtures of various grades, it will be understood that this can be accomplished by any known means for combining the output of the various pipes t, t₁, t₂, etc.

The large exits provided for the currents of gases laden with by-product vapors, and the off-takes provided with suitable control means, allow the perfect maintenance of a gradient of temperature within the whole distillation zone as well as the maintenance of balanced temperature and pressure at each level of said zone, the even flow of gases and their quick exhaust without alteration of the primary grades of condensable hydrocarbon portions whenever formed.

It will be also noted that by locating the orifices for the extraction of the gases and vapors around the periphery of the fuel body, it is not necessary to insert any device with-35 in the fuel mass itself to withdraw therefrom the vapor laden gases, and the mass therefore stands as a body void of empty spaces, except for those which are naturally due to the filling of a column with ordinary 40 solid fuel. Also, since boxes C, C₁, C₂, etc., are filled with vapor laden gases, the fuel body is thus surrounded by a mass of gases which act as an effective insulating agent, thereby assisting in the prevention of con-45 densation of the hydrocarbon portion vapors within the fuel body.

It will be obvious that the invention is not limited to the form shown in the drawings, but is capable of a variety of mechanical embodiments. For example, the hot counter-current of combustible gas need not be generated within the same structure as that in which distillation takes place, but may be supplied thereto in any suitable manner. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:—

1. A continuous low temperature distillation process, applied to a body of fuel mov-

ing through and in contact with a counter-current of combustible heating gas, which comprises maintaining within said moving body of fuel an extended low temperature distillation zone of slow gradient, diverting 70 gas flows from the peripheries of a series of adjacent narrow layers of said distillation zone, each of said flows carrying out of the corresponding layer vapors of one grade of primary hydrocarbon portions, each layer 75 yielding a different grade, and collecting each grade of said vapors separately.

2. A continuous low temperature distillation process, applied to a body of fuel moving through and in contact with a counter-current of combustible heating gas, which comprises maintaining within said moving body of fuel an extended low temperature distillation zone of slow gradient, diverting 80 gas flows through large openings in the peripheries of a series of adjacent narrow layers of said distillation zone, each of said flows carrying out of a corresponding layer vapors of one grade of primary hydrocarbon portions, each layer 85 yielding a different grade ranging from the lightest at the upper part of the distillation zone to the heaviest at the lower part, and collecting each grade 90 of said vapors separately.

3. A continuous low temperature distillation process, applied to a body of fuel moving through and in contact with a counter-current of combustible heating gas, which comprises maintaining within said moving body of fuel an extended low temperature distillation zone of slow gradient, diverting 100 gas flows from the peripheries of a series of adjacent narrow layers of said distillation zone, certain of said flows each carrying out of the corresponding layer vapors of one 105 grade of primary hydrocarbon portions, other flows carrying out a mixture of grades, and collecting each grade and mixture of 110 grades separately.

4. A continuous low temperature distillation process, applied to a body of fuel moving through and in contact with a counter-current of combustible heating gas, which comprises maintaining within said moving body of fuel an extended low temperature distillation zone of slow gradient, diverting 115 gas flows from the peripheries of a series of adjacent narrow layers of said distillation zone, the flows diverted from the hotter layers each carrying out therefrom a mixture of grades of heavier hydrocarbon portions, the flows diverted from the cooler layers each carrying vapors of one grade of lighter primary hydrocarbon portions, and collecting each grade and mixture of 120 grades separately.

5. A continuous low temperature distillation process, applied to a body of fuel moving through and in contact with a counter-current of combustible heating gas, which 130

comprises maintaining within said moving body of fuel an extended low temperature distillation zone of slow gradient, diverting gas flows from the peripheries of a series of adjacent narrow layers of said distillation zone, the flows diverted from the cooler layers each carrying out therefrom a mixture of grades of lighter hydrocarbon portions, the flows diverted from the hotter layers 10 each carrying vapors of one grade of heavier primary hydrocarbon portions, and collecting each grade and mixture of grades separately.

6. A continuous low temperature distillation process, applied to a body of fuel moving through and in contact with a counter-current of combustible heating gas, which comprises maintaining within said moving body of fuel an extended low temperature 15 distillation zone of slow gradient, diverting gas flows from the peripheries of a series of adjacent narrow layers of said distillation zone, each of said flows carrying out of the corresponding layer vapors of one grade of oil, each layer yielding a different grade ranging from low-boiling to high-boiling 20 oils, and collecting each grade of said vapors separately.

7. A continuous low temperature distillation process, applied to a body of fuel moving through and in contact with a counter-current of combustible heating gas, which comprises maintaining within said moving body of fuel an extended low temperature 25 distillation zone of slow gradient, introducing in the hot portion of said fuel body fluids such as steam and carbon dioxide which react endothermically with the fuel, diverting gas flows from the peripheries of 30 a series of adjacent narrow layers of said distillation zone, each of said flows carrying out of the corresponding layer vapors of one grade of primary hydrocarbon portions, each layer yielding a different grade, 35 and collecting the vapors from each layer separately.

8. A continuous low temperature distillation process, applied to a body of fuel moving through and in contact with a counter-current of combustible heating gas, which comprises maintaining within said moving body of fuel an extended low temperature distillation zone of slow gradient, mixing with the fuel materials to absorb heat in 50 various regions of the fuel body, diverting gas flows from the peripheries of a series of adjacent narrow layers of said distillation zone, each of said flows carrying out of the corresponding layer vapors of one grade of 55 primary hydrocarbon portions, each layer yielding a different grade from the lightest to the heaviest, said flows also carrying vapors of said heat absorbing materials, and collecting the vapors from each layer separately.

9. A continuous low temperature distilla-

tion process, applied to a body of fuel moving through and in contact with a counter-current of combustible heating gas, which comprises maintaining within said moving body of fuel an extended low temperature 70 distillation zone of slow gradient, introducing in the hot portion of said fuel body fluids such as steam and carbon dioxide which react endothermically with the fuel, mixing with the fuel materials to absorb heat in various regions of the fuel body, diverting gas flows from the peripheries of a series of adjacent narrow layers of said distillation zone, each of said flows carrying out of the corresponding layer vapors of one grade of primary hydrocarbon portions, each layer yielding a different grade from the lightest to the heaviest, said flows also carrying vapors of 75 said heat absorbing materials, and collecting the vapors from each layer separately.

In testimony whereof I have affixed my signature.
